Specification of Letters Patent.

Patented Jan. 25, 1916.

Application filed May 9, 1912. Serial No. 698,119.

To all whom it may concern:

Be it known that I, ANTON HAAHR, a subject of the King of Denmark, residing at Copenhagen, Denmark, have invented certain 5 Improvements in Folding-Machines, of which the following description, in connection with the accompanying drawings, is a specification, like reference characters on the drawings indicating like parts in the several figures.

This invention relates to folding machines and is herein illustrated in connection with a machine for folding the margins of quarters of boots and shoes.

15 The invention is concerned with certain improvements in machines which are known to the trade as "form folders" in which a considerable extent of the margin of a piece of leather is bent over the edge of the former 20 by the folder, the edges of the former and the folder having a contour which corresponds to that of the margin to be folded. Formers and folders having different contours are used for operating upon pieces of 25 different shape, but for convenience the present invention will be described in the embodiment adapted for operation upon the quarters of Blucher shoes since these quarters present unusual difficulties. Such a 30 quarter is illustrated in Figure 11, the margin to be folded extending from the point A to the point B, the line of fold being indicated by the dotted line. If it is attempted to fold such a margin by using an ordinary

35 folder having the outline of the top, throat and front of the quarter illustrated, a difficulty arises owing to the fact that no direction of movement of the folder can be selected which will cause all portions of the 40 edge of said folder to move transversely across the adjacent edge of the quarter. For example, if the folder is moved in the direction of the feathered arrow the margin at the throat will be properly folded, but the 45 margins at the top Q and front R will not; and this will be true particularly of the front owing to the fact that the direction of movement of the folder very nearly coincides with the line of the edge of the front. 50 Accordingly, such quarters have hitherto been folded by snipping them at the line marked X and using two sets of folders and formers in two separate operations, one set having an outline to correspond to that from 55 A to X and the other an outline to corre-

spond to that from B to X, the approximate directions of movement of the two sets being indicated by the plain arrows. These directions are chosen so as to cause the folder to move as nearly as possible transversely to the edge of the quarter, but it is evident that a movement even approximately transverse to the entire extent of the margin to be folded is impossible owing to the curve of said margin. Moreover, there results at the 60 point X a slight irregularity in the folded edge which must be smoothed out by hand after the two folding operations described above have been completed.

The present invention remedies these defects by providing means for folding the entire margin of the top, throat and front at a single operation. In the illustrative embodiment this is accomplished by main plates which are moved substantially transversely to the edge of the throat and auxiliary end plates so connected with the main plates that by the movement of the main plates transversely of the throat the auxiliary plates are moved substantially transversely of the edges of the front and top of the quarter.

Hitherto when quarters of different sizes were to be operated upon it has been necessary to replace the folder, former and supporting table by others having outlines to correspond to the outlines of the different sizes of the quarters.

Another feature of the present invention consists of a folder, a former and a supporting table comprising sections which may be adjusted to provide for quarters of different sizes. The curve at the center of the throat of quarters is approximately the same for all sizes, the difference lying in the extent of the straight edges at both sides of said center. Consequently in the illustrative embodiment of the invention, wherein a machine for operating upon quarters is shown, the adjustable sections are arranged to slide convergently and divergently in paths which are parallel to the straight portions of the throat of the quarter. Again, quarters of the same size frequently differ in shape or style owing, for example, to variations in the angle 105 between the edge of the top and the adjacent edge of the throat.

Another feature of the invention consists of a folder, a former, and a supporting table comprising sections which may be adjusted 110

to provide for different shapes or styles. In the machine chosen for illustration this feature takes the form of an angularly adjustable section.

5 These and other features of the invention including certain details of construction and combinations of parts will be described in connection with an illustrative machine and pointed out in the appended claims.

10 Referring now to the accompanying drawings, Figure 1 is a plan of the folder, the former and the supporting table in the positions in which they come to rest ready to receive a quarter to be folded; Fig. 2 is a 15 perspective showing one end of the folder; Fig. 3 is a perspective showing the corresponding end of the former; Fig. 4 is a plan of the supporting table; Figs. 5 to 9 inclusive are detail sectional views showing the 20 positions successively occupied by the folder and the former; Fig. 10 is a perspective of one of the templets for facilitating adjustment of the supporting table; and Fig. 11 is a plan of a quarter of a Blucher shoe.

25 The invention is illustrated as embodied in certain improvements in folding machines of the type illustrated in British Patent No. 5436 of 1907 and more particularly in connection with certain improvements in the 30 supporting table, the former and the folder. The table as a whole is indicated at T, the folder at F, and the former at C. The mounting of the stationary table and the mechanism for moving the folder and the 35 former in proper sequence may be of any suitable construction such, for example, as is shown in the patent referred to and will not be described in detail. Before proceeding, however, to a detailed description of the 40 invention, a general description of the operation of the machine will be given.

Referring now more particularly to Figs. 1 and 5 to 9 inclusive, the folder F comprises an upper main folding plate 1 and a lower 45 stop plate 3 held normally in the relative position shown in Fig. 5 by a spring 5, the folding plate being adapted to be attached to a movable part of the machine by a thumb screw 7, see Fig. 1. The table, which does 50 not move, is provided with a socket 9 to receive an eccentric, not shown, which clamps the table to the base of the machine. The former C comprises a body or carrier 11 and a main forming plate 13 which may be 55 moved relatively to each other so as to present the forming plate to and withdraw it from the line of fold at the proper time. The forming plate is provided with two sockets 15, see Fig. 1, which coöperate with 60 clamps 17 fast to spring-pressed plungers slidable in hollow arms 19 which are in turn fast to rods 21, said rods being slidable in tubular arms 23. The arms 23, in the operation of the machine, are caused to be lowered 65 and the rods 21 to be slid forward and back-

ward in said arms to advance and retract the forming plate 13. Pins 25 depending from the tubular arms 23 serve to hold the carrier 11 stationary during the forward and backward movement of said forming plate. 70

In the following description of the operations of the parts "forward" will signify downward in Fig. 1 and to the left in Figs. 5 to 9. Starting then with the parts in the position shown in Fig. 9 which is the initial 75 and the final position, the quarter 100 is placed upon the table T and slid beneath the folding plate 13 until its edge contacts with the gage 27. The tubular arms 23 which support the former are then brought down 80 thereby clamping the quarter in the position shown in Fig. 5. The folder is next moved upwardly to the position shown in Fig. 6 thereby upsetting the margin of the quarter about the edge of the forming plate 13. 85 Thereupon the folder is moved forwardly with the result that the folding plate 1 moves over the table T and the spring 5 is compressed, the parts then being in the position shown in Fig. 7. The rods 21 are then 90 moved forwardly to withdraw the forming plate 13 from beneath the overturned margin as shown in Fig. 8; the folding plate is moved downwardly to press the fold, and finally the parts are returned to the normal 95 position shown in Fig. 9. The movements indicated above all take place during the operation of the machine shown in the patent referred to wherein the mechanism for producing them is described in detail. 100

When the margin to be folded is a straight one, or when the curve is a single one of large radius, the mechanism described in the patent and briefly outlined above is satisfactory, but when it is desired to fold a 105 margin having sharp curves and consequently edges which extend at an angle to one another, a difficulty arises from the fact that the direction of movement of the folder is not substantially transverse to all portions of the edge of the margin to be folded. In order to promote brevity, the folding of the margin of a quarter for a Blucher shoe will be described below, but it should be understood that the invention is limited in 110 no way to the folding of this particular piece. Referring now to Fig. 11 such a quarter is shown together with a feathered arrow which indicates the direction of movement of the main folding plate 1 when the 115 margin of the quarter is being bent over the forming plate, the direction of said movement being substantially normal to the base of the curve of the throat. This direction of movement, however, is oblique to the top 120 edge indicated at Q as well as to the front edge indicated at R. The present invention is directed to the folding, at a single operation, of all three edges, and to this end auxiliary folding plates are caused by the for- 125 130

ward movement of the main folding plate 1 to wipe over the top and front edges Q, R, in directions substantially normal to said edges. Inasmuch, however, as the two auxiliary folding plates are similar in construction and mode of operation only one will be described in detail.

- Projecting from and fast to or integral with the main folding plate 1 (see Figs. 1 and 2) is an extension 29 provided with a rib or slide 31 which fits in a dove-tailed groove 33 in a similar extension 35 on the stop 3 so that these extensions move with respect to each other when the parts 1 and 3 are moved from the position shown in Fig. 6 to that shown in Fig. 7 or from the position shown in Fig. 8 to that shown in Fig. 9; and this relative movement is utilized to actuate the auxiliary folding plate 37. Mounted upon the upper side of the extension 29 and adjustable for a purpose presently to be described is an actuating plate 39 which, during the operation of the machine, is held in adjusted position by thumb screws 41 which pass through slots 43 and are threaded into the extension 29. Mounted upon the under side of the lower extension 35 is a second actuating plate 45 similar to the plate 39 and similarly held in adjusted position. For the present the adjustment need not be considered since its purpose is merely to provide for quarters of different sizes, the two plates 39 and 45 being always adjusted in unison. The auxiliary folding plate 37 is provided with slots 47 which are inclined to the direction of movement of the folder and with slots 49 which are substantially transverse to said direction. Pins 51 which, during the folding operation, are held rigid with the actuating plate 45 extend through the inclined slots 47, and similar pins 53 similarly held with respect to the actuating plate 39 extend through the transverse slots 49. When now the parts are moved from the position shown in Fig. 6 to that shown in Fig. 7 the plate 39 will move forwardly with respect to the plate 45 and will tend to carry with it the auxiliary plate 37. Owing, however, to the inclined slots 47 and the pins 51, the effect of this tendency will be to move the auxiliary plate in a direction approximately at right angles to the forward movement of the folder. At the same time a similar folding plate 137 provided with similar slots (indicated in dotted lines in Fig. 1) is similarly moved by actuating plates, one of which is shown at 139, to wipe over the front edge R of the quarter. There is thus provided a pair of auxiliary folding plates which are caused by the forward movement of the main folding plate to move toward each other in directions which are at an angle and substantially transverse to the direction of movement of said main plate.

The slots 49 and 47 have been shown extending respectively transverse to and inclined to the direction of movement of the folder. It should be understood, however, that this particular relation is not essential since it is evident that by varying the inclination of one set of slots with respect to that of the other the direction of movement of the auxiliary folding plate 37 with respect to that of the main plate may be varied as may be desired.

As has been stated, the present invention provides means for adjusting the machine to accommodate quarters of different sizes, and it is for this purpose that the actuating plates 39 and 45 are made adjustable. The plate 29 is provided with a guide 59 which is received in a dove-tailed groove 61 in the plate 39. The plate is also provided with a dove-tailed groove (not shown) which is parallel to the guide 59 and receives a dove-tailed guide (also not shown) carried by the plate 39. The second groove and guide act in conjunction with the guide 59 and groove 61 and serve merely to strengthen the device by providing an extra slide bearing. The edge of the main folding plate 1 is also undercut at 60 to receive the beveled edge of the plate 39. The lower actuating plate 45 is similarly attached to and adjustable on the extension 35 and, as stated above, the two plates 39 and 45 are always adjusted in unison.

Referring now to the left-hand portion of the folder as viewed in Fig. 1 there is provided in the extension 129 a dove-tailed groove or guideway 161 in which the actuating plates, the upper of which is shown at 139, are slidable, said plates being formed with slots, one of which is shown at 143, through which extend clamping screws, one of which is shown at 141. Upon the upper slidable plate 139 and upon a plate 67, the adjustment of which will be presently described, are mounted gages 65 and 68 respectively which, taken with the gage 27, correspond in outline to that of the portion of the quarter which is to be folded. As has been stated, the curve at the throat of quarters is substantially the same for all sizes. The curve at the central portion of the edge gage 27 corresponds to this curve, but the ends are straight so that when the end pieces are adjusted toward or from each other the continuity of the operative edge presented by the three gages is not broken.

With different styles of quarters it often happens that the angle which the top edge Q forms with the adjacent edge of the throat varies, and it is desirable that provision be made for adjusting the parts of the folder so as to adapt the folder to conform to this variation in the shape of quarters. Accordingly the auxiliary folding plate 37 is held between and carried by two angularly 130

adjustable plates or sectors 67 and 69 which are mounted respectively upon the upper actuating plate 39 and the lower actuating plate 45. These angularly adjustable plates have the general outline of a sector of a circle the curve of their outer edges 70 being segments of circles struck from a point in a vertical axis indicated at A in Fig. 2. Inasmuch as the two angularly adjustable plates 67 and 69 are symmetrical, similarly mounted, and arranged to be adjusted in unison, only one of them need be described in detail. The upper actuating plate 39 is cut away on its upper side to provide a seat or socket for the angularly adjustable plate or sector 67 and is provided with a curved guide 71 which is received in a correspondingly curved slot in the sector 67, the curves of the edges of the guide and the walls of the slots being segments of circles struck from the same center as that of the curve 70. A curved slot 73 struck from the same center permits a clamping screw 75 to hold the sector in adjusted position. With the construction thus far described it is evident that the pair of sliding plates at each end of the folder may be adjusted to provide for quarters of different sizes and that the sectors 67 and 69 may be adjusted angularly to provide for quarters of different shapes. Attention is here directed to the fact that the pins 53 are carried by the upper sector 67 and the pins 51 by the lower sector 69, so that angular adjustment of the sectors effects angular adjustment of the auxiliary folding plate 37.

It is of course desirable that a similar set of adjustments be provided for the table upon which the quarter is supported during the folding operation so that the edge of the table may correspond to the edge of the fold. Referring now to Fig. 4 two sliding plates 77 and 79 are provided having slots 81 to receive clamping screws 83, said plates having projecting guides on their bottoms which fit into suitable grooves or guideways in the table. Pivotally mounted at 84 on the sliding plate 79 is an angularly adjustable plate 85. In order that the plate 85 may be held in adjusted position, a slot 87 in said plate has a countersink, and upon the ledge thus formed rests a slotted slide 89. A screw 91 passes through the slot in the slide and is threaded into the table. The front edge of the table is of full thickness from the point 93 to the point 95. The remaining portion of the front edge is reduced by the width of the material cut away to make room for the plates 77 and 79, and the right hand edge of the swinging plate 85 has a depending flange 291 to provide an edge which is of approximately the same thickness as that of the table. The curve between the points 93 and 95 corresponds to the curve at the central portion of the gage 27 of the folder,

so that with the construction described above the contour of the operative edge of the table may be made to correspond to the combined contour of the gages 25, 27 and 63 of the folder in their different positions.

As has been stated, the contours of the operative edges of the folder, the former and the table are identical during the operation of the machine, and are adjusted before said operation to conform to the particular size 75 of quarter which is to be folded. It is desirable that provision be made for facilitating the adjustment of one of these three members so that it may be adjusted quickly and serve then as a form or pattern to aid 80 in the adjustment of the other two; and in the illustrative machine the supporting table has been chosen. To this end there is provided a series of templets each preferably marked with the number of the size of the 85 quarter to which it corresponds; and these templets are adapted to be inserted between the sliding members 77 and 79 of the supporting table. One of these templets is shown in place at 80 and a larger one alone 90 in Fig. 10. When changing from one size of quarter to another the table may be quickly adjusted by removing the old templet and replacing it by the proper one, the slides 77 and 79 being then moved up against 95 the new templet and locked in position by the screws 83.

The former C is constructed so as to permit the same adjustments for size and angle as are the folder and the supporting 100 table. It is also provided with a main forming plate and with auxiliary forming plates constructed and arranged to be moved similarly to the manner in which the main and auxiliary plates of the folder are moved. 105 The body or carrier of the former is arranged to be raised and lowered by the upward and downward movements of the tubular arms 23, but to be held from movement with respect to said arms by the pins 110 25 during the forward and backward movements of the forming plate which are brought about by the forward and backward movements of the rods 21 to which the arms 19 are attached (see Figs. 5 to 9). 115

Referring now more particularly to Fig. 3 there is mounted in the carrier or body a main forming plate 101 having slots 103 to receive guide pins 105 which determine the direction in which said forming plate 120 shall move with respect to the carrier. Slidably mounted upon said carrier is a plate 107 similar to the plate 29 of the folder and similarly held in place by a clamping screw 109 which passes through a slot 111 12 and is threaded into the carrier. Mounted upon the plate 107 is a sector 113 similar to the sector 67 and similarly held in place by a clamping screw 115 which passes through a curved slot 117; and this sector carries 11

loosely in its outer portion an auxiliary forming plate 119 by means of pins 121 which pass through inclined slots 123 in said auxiliary forming plate. In order to permit the sliding adjustment of the plate 107 without breaking the continuity of the effective edge of the main and auxiliary forming plates, there is slidably mounted in the main forming plate 101 an extension 223 having integral therewith two slides 125 and 127 which are held in suitable guideways formed in the main forming plate 101. The operative edge of the extension 223 is beveled to correspond to the bevel of the main forming plate 101 so that there is practically no break in the edge at the point where the two edges meet. In order to permit angular adjustment of the sector 113 and with it the auxiliary forming plate 119, said plate is formed with a curved hook 129 which fits about a second curved hook 131 formed on the extension 223, said second hook in turn fitting about a suitably shaped bearing portion of the plate 119 so that said plate and the extension 223 are in effect pivoted together about an axis which contains the center of curvature of the hooks 129 and 131. Referring now to Fig. 1, the other end of the former is provided with a sliding plate 133 held in adjusted position by a clamping screw 135 and with a second auxiliary forming plate 138 having guides 140 which are slidably mounted in suitable ways in the main forming plate 101. Pins 142 carried by the plate 133 passes through inclined slots 144 in the auxiliary forming plate. With the construction described above, movement in the upward direction of the main forming plate 101 as viewed in Fig. 1 will cause the auxiliary forming plates 119 and 138 to move away from each other while movement in the downward direction of the main plate 101 as viewed in the same figure will cause movement of the auxiliary plates toward each other. The purpose of this construction is to insure that the auxiliary forming plates 119 and 138 shall be withdrawn from the top Q and front R of the quarter when the main forming plate 101 is withdrawn from the throat of the quarter.

The operation of the machine is as follows: The proper templet is placed between the sliding members 77, 79 of the table and the member 85 adjusted angularly if such adjustment is required. The sections of the folder and the former are adjusted in conformity with the adjustment of the parts of the table. The quarter is then placed upon the table beneath the former with its edge against the gages 63, 27, 65. A treadle-operated clutch (not shown) is thrown in to cause the driving shaft (also not shown) to make one revolution with the result that the folder rises, the main and auxiliary fold-

ing plates bend the margin over the edge of the main and auxiliary forming plates, then, after said forming plates have been withdrawn, press the fold against the table, and finally return to normal position.

Although the invention has been set forth in connection with a machine for folding pieces of material of a particular shape, it should be understood that the invention is not limited in the scope of its application to the particular shape of material or to the particular machine shown and described.

Having thus described my invention, what I claim and desire to secure by Letters Patent of the United States is:

1. In a machine of the class described, a folder, a former and a supporting table, each comprising a main section and an angularly adjustable section, and means for holding said adjustable sections in position.

2. In a machine of the class described, a folder comprising a main section, a slidably adjustable section connected with said main section, an angularly adjustable section, also connected with said main section, and means for holding said adjustable sections in adjusted position.

3. In a machine of the class described, a folder comprising a main section, an edge gage mounted thereon, an adjustable section, and a second edge gage mounted on said adjustable section, the outline of the operative faces of said gages corresponding to the outline of the portion of the blank to be folded, the construction and arrangement being such that the continuity of the outline presented by said gages is preserved in the different positions of said adjustable sections.

4. In a machine of the class described, a folder comprising a main section, an edge gage mounted thereon, an angularly adjustable section, and a second edge gage mounted on said adjustable section, the outline of the operative faces of said gages corresponding to the outline of the portion of the blank to be folded, the construction and arrangement being such that the continuity of the outline presented by said gages is preserved in the different positions of said angularly adjustable section.

5. In a machine of the class described, a folder comprising a main section, an edge gage mounted thereon, an adjustable section slideable with respect to said main section in a direction parallel to the adjacent face of said gage, and a second edge gage mounted upon said adjustable section, the end of said second gage being approximately in contact with the face of the said first gage in the different positions of said slideable section.

6. In a machine of the class described, a folder comprising a main section, an edge gage mounted thereon, a section angularly adjustable with respect to said main section, and a second edge gage mounted upon said

angularly adjustable section, the end of the second gage being approximately in contact with the face of said first gage in the different angular positions of said adjustable section.

7. In a machine of the class described, a folder comprising a main section provided with an extension, a second section connected with said extension and slidably adjustable with respect thereto, a third section connected with said second section and angularly adjustable with respect to said second section, and means for locking said sections rigid with one another in adjusted position.

8. In a machine of the class described, a folder comprising a main folding plate, auxiliary folding plates extending at an angle thereto, said auxiliary plates being adjustable along the edge of said main plate, one of said auxiliary plates being angularly adjustable, and means for holding said auxiliary plates in adjusted position.

9. In a machine of the class described, a sectional folder having the outline of the edge of a quarter at the top, throat and front, the sections being constructed and arranged to be adjusted to form similar contours corresponding to quarters of different sizes and to form dissimilar contours corresponding to different shapes of quarters of the same size.

10. In a machine of the class described, a former comprising a main section, a slidably adjustable section connected with said main section, an angularly adjustable section also connected with said main section, and means for holding said adjustable sections in adjusted position.

11. In a machine of the class described, a sectional former having the outline of the edge of a quarter at the top, throat and front, the sections being constructed and arranged to be adjusted to form similar contours corresponding to quarters of different sizes and to form dissimilar contours corresponding to different shapes of quarters of the same size.

12. In a machine for folding the margin of a quarter at the top, throat and front, a former comprising a main forming plate movable toward and from the throat, auxiliary forming plates and connecting means between said plates responsive to movement of the main plate for moving the auxiliary plates in directions substantially transverse to the top and front of the quarter.

13. In a machine of the class described, a folder comprising a main folding plate provided with an extension, pins held rigid with

said extension during the folding operation, a stop with respect to which the main folding plate moves, pins held rigid with respect to said stop, and an auxiliary folding plate having slots to receive said pins.

65

14. In a machine of the class described, a folder comprising a stop and a main folding plate movable with respect thereto, an auxiliary folding plate having slots extending approximately transverse to the direction of movement of the main folding plate and other slots extending at an angle to said direction of movement, pins carried by said main plate and arranged to enter said transverse slots, and pins carried by said stop arranged to enter said inclined stops.

15. In a machine of the class described, a sectional folding member, a sectional forming member, and a sectional table, said members being capable of adjustment for folding articles of different sizes, in combination with a templet corresponding to one size of article to be folded, said templet being adapted to be inserted between the sections of one of said members whereby the adjustment of the three members is facilitated.

16. In a machine of the class described a folder comprising a main section, a section slidably adjustable thereon, a section angularly adjustable on said slideable section, and means for holding said sections in adjusted position.

17. In a machine of the class described a folder comprising a main section provided with an extension, a second section slidably adjustable on said extension, a third section angularly adjustable on said second section, and means for holding said sections in adjusted position.

18. In a machine of the class described a former comprising a main section, a section slidably adjustable thereon, a section angularly adjustable on said slideable section, and means for holding said sections in adjusted position.

19. In a machine of the class described a folder comprising a main folding plate and an angularly adjustable auxiliary folding plate connected therewith, and means responsive to movement of said main folding plate in one direction for moving said auxiliary plate in a different direction.

In testimony whereof I have signed my name to this specification in the presence of the subscribing witnesses.
